FIG. 1 is a top, end, side perspective view of a watering hose showing our new design;

FIG. 2 is a side view thereof, with the opposite side being a mirror image thereto;

FIG. 3 is an end view thereof, with the opposite end being a mirror image thereto; and,

FIG. 4 is a top view thereof, with the bottom being a mirror image thereto.

The broken line disclosures of the internal hose diameter and structure show unclaimed detail only and form no part of the claimed design.
